UNITED STATES PATENT OFFICE.

GEORGE W. MENOUGH, OF WELLSVILLE, OHIO.

SAD-IRON.

SPECIFICATION forming part of Letters Patent No. 328,800, dated October 20, 1885.

Application filed March 29, 1884. Serial No. 126,070. (No model.)

To all whom it may concern:

Be it known that I, GEORGE W. MENOUGH, a citizen of the United States, and a resident of Wellsville, in the county of Columbiana and State of Ohio, have invented certain new and useful Improvements in Sad-Irons; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved sad-iron. Fig. 2 is a similar view of the body of the iron with the detachable handle removed. Fig. 3 is a bottom plan of the plate which forms part of the removable handle, and Fig. 4 is a longitudinal vertical sectional view 20 through the middle of the complete sad-iron.

Similar letters of reference indicate corresponding parts in all the figures.

My invention has relation to that class of sad-irons which are provided with detachable 25 or removable handles, so that one handle may serve the purpose of a number of irons; and it consists in the improved construction of a sad-iron of that type, as will be hereinafter more fully described, and particularly pointed 30 out in the claims.

In the accompanying drawings, A denotes the body of the iron, which has a plated bottom, a, and may be of any suitable size, shape, weight, and material. This body is cast with 35 two depressions or recesses, one in the front part and one in the rear part, on the top of the iron, as shown at B and C, respectively. Between and in a line with these recesses are two upwardly-projecting studs, D D, having 40 projecting lips or hooks E at their upper ends.

F is a plate corresponding in shape or general outline to the top of the iron, and provided on its under side with two downwardly-projecting lugs, G and H, which are recessed 45 or socketed, as shown at h h, to receive the handle-bars I I, the lower ends of which are permanently fastened by suitable means in the said sockets.

Between the downwardly-projecting lugs are 50 two slots or openings, J J, between which is a stud or pin, K, forming a pivot for the circular

disk or plate L upon the top of plate F. This disk is provided with a knob or handle, M, for turning it, and has two slots or openings, N, adapted to register with the apertures J in 55 plate F. The slots N have extensions O, and are bordered on the outside by wedge-shaped projections P P, inclined in opposite directions upon the periphery of disk L. This disk, pivoted upon its stud or vertical spindle K, rests 60 in a circular depression or recess, Q, in the top of plate F, which said recess is provided on one side with a stop, R. Thus it will be seen that the slotted disk L may be moved or rotated by means of its knob or handle M 65 forward and back between the stop R and the handle-bar I at the rear end of the sad-iron.

From the foregoing description, taken in connection with the drawings, the manner of attaching or detaching the handle will be 70 readily understood. By turning disk L so that its slots or apertures register with the apertures in plate F the latter may be placed upon the top of the body A, with its lugs G H projecting down into the recesses E and C, respectively, the hooked studs D E projecting up through the apertures. By then turning disk L so that its knob will strike against the rear handle-bar I the disk will be moved so as to bring its wedges to bear against the under side 80 of the hooks E E, and thus lock the handle firmly in place upon the top of the body A. To detach the handle, the knob is simply turned in the opposite direction until it strikes the fixed stop R, when plate F may readily be lifted 85 off of the top of iron, the hooked studs D E slipping through the extensions or enlargements O in the disk-slots N.

I am aware that sad-irons have been made with the handle attached to a plate provided 90 with a horizontally-pivoted cam-plate adapted to be turned so as to catch under a hooked lug projecting from the upper side of the body of the iron through a perforation in the plate, and I do not wish to claim such construction, 95 broadly; but I am not aware that such cam-plate has been provided with wedge-shaped projections adapted to wedge under hooked lugs upon the iron, which wedge-shaped projections facilitate the releasing of the plate from 100 the iron when the hooked lugs have contracted upon the projections by the cooling off of the

iron, causing them to clamp the cam-plate more firmly than when the iron was hot, and consequently expanded; neither am I aware that the ends of the lugs in which the handle 5 is fastened have projected below the surface of the handle-plate fitted into recesses in the top of the iron, whereby the handle-plate is prevented from playing upon the body of the iron; and

10 I therefore claim—

15 1. The combination, with the body of a sad-iron having recesses in its upper face and pro-
vided with upwardly-projecting hooked studs, of a handle-plate fitting upon the body of the iron, and having the lugs into which the ends of the handle are secured projecting into the recesses in the body of the iron, and having a cam-plate for engaging the hooked lugs, as and for the purpose shown and set forth.

2. The combination, with the body of the sad- 20 iron having two upwardly-projecting hook-shaped lugs upon its upper face, of a handle-plate fitting upon the said face, having the hooked lugs projecting up through it, and a circular cam-plate pivoted horizontally upon 25 the handle-plate, having a handle for turning it, and having wedge-shaped projections at its rim bearing under the hooked ends of the lugs, as and for the purpose shown and set forth.

In testimony that I claim the foregoing as my 30 own I have hereunto affixed my signature in presence of two witnesses.

GEORGE W. MENOUGH.
